SELF-ALIGNING BELT IDLER

Gordon F. Dodge, Columbus, Ohio, assignor, by
means assignments, to The Jeffrey Manufacturing Company, a corporation of Ohio

Application December 7, 1943, Serial No. 513,310

1 Claim. (Cl. 198-202)

This invention relates to a self-aligning belt idler.

An object of the invention, therefore, is to provide an improved self-aligning belt idler.

A further object of the invention is to provide a very efficient self-aligning belt idler which includes a swingable idler roller supporting frame which swings on an inclined axis which passes through, or substantially through, the center of gravity of the swingable frame and those parts which are carried by it and which includes independently rollable idlers.

Other objects of the invention will appear hereinafter, the novel features and combinations being set forth in the appended claim.

In the accompanying drawing,

Fig. 1 is a transverse sectional view of a belt conveyor including troughing and return self-aligning belt idlers incorporating my invention;

Fig. 2 is a sectional view taken on the line 2-2 of Fig. 1, looking in the direction of the arrows;

Fig. 3 is a sectional view taken on the line 3-3 of Fig. 1, looking in the direction of the arrows; and

Fig. 4 is a sectional view taken on the line 4-4 of Fig. 3, looking in the direction of the arrows.

Self-aligning belt idlers have been the subject of considerable investigation and numerous proposed arrangements of parts have been made with varying degrees of complication, effectiveness and satisfactory overall results. I have discovered that none of the prior art devices provides an efficient, simple, yet highly effective combination of parts because in each prior art device of which I am aware there are one or more deficiencies.

The idlers of my invention in the two embodiments, provide particular combinations of elements which make for extreme simplicity, maximum effectiveness and general overall satisfactory operation which is unattainable with any known prior art device.

Referring first to Fig. 1 of the drawing, I have shown a conveyor including a main frame 10 formed of longitudinally extending channel members 11, 11, which are interconnected at intervals by cross members, not illustrated. Extending laterally across the tops of the channel members 11, 11 is a stationary supporting base 12 in the form of an inclined angle member having end brackets which attach it to said channel members 11, 11. The angle member or base 12 forms the supporting base of a troughing type self-aligning belt idler mechanism 13 which sup-

ports the upper or load carrying run of an endless conveyor belt 14 which extends between head and tail pulleys of the conveyor which are not illustrated. The return run of the belt 14 is supported on a flat self-aligning belt idler mechanism 15.

Attention is now directed to Figs. 1 and 2 of the drawing and to the troughing type self-aligning belt idler mechanism 13. In addition to the supporting base 12, said mechanism 13 includes a supporting stub shaft 16 which has a base 17 rigidly attached to the supporting base 12. Mounted upon the stub shaft 16 and supported by spaced anti-friction roller bearings 18 and 19 is a hub or casting 20 provided with a removable enclosing cap 21 at its top and a labyrinth grease seal 22 at its bottom. A grease fitting 23 is provided so that the bearings 18 and 19 may be lubricated. The hub or casting 20 is attached to the center of a swingable or pivoted frame 24 which is in the form of an inverted angle member, the outer ends of which are bent upwardly to provide the troughing type idler assembly.

Mounted upon the frame 24 are two intermediate supporting brackets or feet 25 and two end brackets or feet 26. The four brackets or feet 25 and 26 support three idler shafts, one of which is seen at 27 in Fig. 2 of the drawing. These three shafts support three independently rotatable idlers or rollers 28, 29 and 30. The center idler or roller, 29 is mounted upon a horizontal axis which passes through a vertical plane through the axis of the swingable frame 24, this axis being, of course, the axis of the shaft 27. The inclined outer rollers or idlers 28 and 30 have axes which lie in this same vertical plane but they are oppositely inclined with respect thereto.

With reference to Figs. 1 and 2 of the drawing it will be seen that the axis of the stub shaft 16 and consequently the pivotal or swinging axis about which the swinging frame 24 pivots, lies in a vertical plane which is transverse to the normal axis of the swingable frame 24 which is also transverse to the normal axes of rotation of the idlers 28, 29 and 30.

There is another and exceedingly important characteristic of this swingable axis about which the swingable frame 24 pivots which, of course, is the axis of the stub shaft 16, and that is, this axis while lying in the above mentioned vertical plane also preferably passes through or near the center of gravity of the assembly of all of the swingable parts which swing with and are carried

by or attached to the swingable frame 24 which includes, of course, the idler rollers 28, 29 and 30, the brackets 25 and 26 and the hub or casting 20. In actual practice, this axis is preferably slightly above this center of gravity because in normal operation there is a load carried by this swingable troughing belt idler mechanism assembly which includes the weight of a portion of the belt 14 and the load on it. It may be stated that the limits within which this axis may be positioned in this vertical plane are defined by a line through the axis of the shaft 27 and the roller 29 thereon and a line through the top of said horizontal roller 29. It is of particular importance to note not only the location of this axis about which the swingable frame 24 swings but it is also quite important to note that the rollers or idlers 28, 29 and 30 are all independently rollable and are not interconnected. It is this particular combination which applicant has found to be simple but very efficient in operation in a troughing type belt idler.

It is furthermore to be noted that considering the direction of travel of the belt 14 over the troughing idler mechanism 13, the swinging axis of said frame 24 is to the rear of the axes of the rollers 28, 29 and 30.

Considering now the structure of the return or flat belt idler mechanism 15, the same general considerations and general construction above described fully applies though in certain details I have illustrated different construction. The flat belt idler mechanism 15 includes a stationary supporting base 31 in the form of an inverted angle member which is provided at its ends with hangers 32, 32 by which it is connected to the bottoms of the channel members 11, 11. Adjacent its center, the base 31 is provided with a pivot socket or casting 33 which has a base 34 bolted or otherwise attached to the supporting base 31. The pivot socket or casting 33 carries an upwardly inclined pivot pin 35 which is journaled in said socket for pivotal movement. At its upper end the pivot pin 35 is rigidly connected to a swingable or pivoted frame 36 which is a composite structure formed of a hollow tube 37 at the center of which is attached the pin 35 and through which there extends an idler or roller supporting shaft 38 which is rigidly but removably connected to the tube 37 through sleeves, one of which is seen at 39 and set screws, one of which is seen at 40. A drip shield 41 is provided at the center of the swingable frame 36 and extends over the pivot socket 33. At opposite ends there are idlers or rollers 42 and 43 which are mounted on the shaft 38 by anti-friction bearings, one of which is seen at 44. It is of particular importance to note that the shaft 38 is a dead shaft and not a live shaft, that is, it does not rotate in the swingable frame 36 or tube 37. Furthermore, it is of importance to note that the idler rollers 42 and 43 are mounted for independent rotation because I have found that if these idler rollers are connected to rotate together, either through a shaft or a single roller, the maximum efficiency of operation is not realized, as it is in my device.

From the above description it is evident that the swingable or pivoted frame 36 is rigidly attached to the pivot pin 35 and swings about the axis of said pin 35. This axis lies in a vertical plane which is transverse to the normal axis of said swingable or pivoted frame 36 and to the axes of each of the rollers 42 and 43 which co-

incides with the axis of said swingable or pivoted frame 36. Furthermore, in this case the pivotal axis of said frame 36, or in other words, the axis of the pivot pin 35, passes through the axis of 5 said swingable or pivoted frame 36 and, in common with the troughing belt idler mechanism 13, it also passes through the center of gravity of the swingable or pivoted frame 36 and those parts carried by it, including the idlers or rollers 42 and 43.

In the case of the flat type self-aligning belt idler illustrated in detail in Figs. 3 and 4 of the drawings, the center of gravity of the swingable frame 36 and those parts carried by it is along 15 its own axis and the presence of the belt 14 and the load on its in nowise changes the location of the center of gravity. In other words, in this regard the flat belt idler mechanism of 15 is a special case of the troughing belt idler mechanism 20 13. In common with the troughing belt idler mechanism 13, the flat belt idler mechanism 15 is also one in which considering the direction of travel of the belt 14 over the troughing idler mechanism 13 the swinging axis of the frame 24 25 is to the rear of the axes of the rollers 28, 29 and 30.

It may further be pointed out that to provide for lubrication of the pivot pin 35 in the socket 33, the bottom end of the socket 33 is closed by a 30 plug 45 provided with a grease fitting 46.

Operation of the belt idler mechanisms 13 and 15 is entirely automatic, being induced by unbalancing of loads about the inclined pivots. A belt running to one side depresses the heavy side, but 35 due to the inclined pivot a downward movement must be accompanied by a swinging movement and this swinging movement is in the correct direction to deflect the belt back to a central position.

40 It should be noted particularly that with this construction the tendency for correction is immediate upon development of any unbalance in the supported load and does not wait upon a sufficient deviation from alignment for the edges of 45 the belt to actuate some auxiliary mechanical device for swinging the idler. Further, not depending upon such auxiliary mechanisms, these are eliminated along with their frequent damaging of the edges of the belt and displacement 50 of occasional overhanging lumps of the load being carried.

It is to be understood that in a complete conveyor there will be at desired intervals troughing idler rollers 13 either with or without return idler 55 rollers 15, or vice versa, and normally there will be plain troughing and belt supporting idlers between the self-aligning idlers.

It is further to be noted that the idler mechanism 15 is not limited to return belt operation. 60 For example, there are many cases in which the upper or working run is a flat belt and in such cases the flat belt mechanism may be employed. It is further obvious that the idler mechanisms 13 and 15 may be employed each without the 65 other in any case where it is desired.

Obviously those skilled in the art may make various changes in the details and arrangement of parts without departing from the spirit and scope of the invention as defined by the claim 70 hereto appended and I wish therefore not to be restricted to the precise construction herein disclosed.

Having thus described and shown an embodiment of my invention, what I desire to secure by 75 Letters Patent of the United States is:

A belt idler assembly adapted to support and train a moving belt including a swingable tubular frame member having a pivot shaft extending at right angles to its longitudinal axis, a sleeve member associated with each end of said frame member, a shaft extending through said frame member along its longitudinal axis through said sleeve members and carried by the latter, means securing said shaft against movement relative to said members, an idler roller adjacent each of said sleeve members, anti-friction bearing means associated with each of said sleeve members sup-

porting said idler rollers for free rotation thereon, a stationary supporting base for said frame member in the form of an inverted angle member having hangar means adjacent its ends, and 5 an upwardly inclined pivot socket having a mount adapted to be received by said inverted angle member, said base supporting the pivot shaft of said tubular frame in an inclined position whereby said frame may pivot on its pivot shaft to train 10 a belt carried by the idler rollers.

GORDON F. DODGE.
